UNITED STATES PATENT OFFICE.

MARGARET B. WILLIAMS, OF CHICAGO, ILLINOIS.

LOCK.

1,234,519.

Specification of Letters Patent. Patented July 24, 1917.

Application filed July 3, 1915. Serial No. 37,956.

To all whom it may concern:

Be it known that I, MARGARET B. WILLIAMS, a citizen of the United States, residing at Chicago, in the county of Cook and 5 State of Illinois, have invented certain new and useful Improvements in Locks, of which the following is a specification.

My present invention relates to locks, and more particularly to an improvement in a 10 combined latch and lock, its object being to provide a positive locking element within the latch of the lock.

A further object of my invention is to provide a simple practical lock which is generally adapted for use in residences and 15 other buildings.

Having these and other objects of general design and utility in view, I have illustrated an operative construction embodying my invention in the accompanying drawings, in which:—

Figure 1 is a fragmental elevation of my lock in locked position;

Fig. 2 is a horizontal section thereof taken 25 on line 2—2 of Fig. 1;

Fig. 3 is a view similar to Fig. 1 showing my lock in open or unlocked position;

Fig. 4 is a sectional detail of the latch bar, and—

Fig. 5 is a fragmentary sectional detail of the co-acting knob spindles.

Fig. 6 is an enlarged sectional detail of the connecting ends of the door knob spindles.

Fig. 7 is an enlarged sectional detail taken at substantially right angles thereto, and

Fig. 8 is a transverse section taken on line 8—8 of Fig. 6.

Similar reference characters refer respectively to similar parts throughout the several views.

My lock comprises the usual rectangular casing 10, embedded in the door 11, and is 45 provided with inner and outer door knobs 12 and 13 respectively, terminating in their respective shanks 14 and 15, and adapted to meet within a collar 16 journaled in the lock casing. Lying diametrically opposite 50 one another and integral with the collar 16 are lugs 17, adapted to abut corresponding lugs 18 upon a spring controlled latch plate 19, horizontally reciprocable within slides 20 and pins 21 projecting from the walls 55 of the casing 10, (Fig. 1). A lever 22 is

normally held in engagement with lugs 23 and 24 protruding from said plate 19; and pivoted to the lower end of this lever, at 25, is the latch bar 26, which extends through the casing 10, at 10^a, and into a keeper 27 in the door jamb, within which and transverse thereto is mounted a lock bar 36. A contraction spring 28 connects the upper end of the lever 22 with the casing of the lock.

The latch bar 26 is a substantial shell, within which reciprocates a bar 29, yieldingly held in the position shown in Fig. 1, by a contraction spring 30. Pivoted at 31 to the forward edge of and within the latch 70 bar 26, is a pair of grapples 32 and 33, respectively adapted to lock upon said lock rod 36; the inner end of the member 32 is pivoted to a link 34 pivoted to the bar 29, and the inner end of the member 33 abuts 75 an inclined slide 35 on the face of the bar 29, so that when the bar is forced forward as shown in Fig. 4, the grapples 32—33 will open, as shown, and thus release their grip upon the rod 36.

As a means for reciprocating the bar 29, I provide a strip of metal ribbon 37, adapted to pass over the reduced portion 14^a of the spindle 14 on the inside door knob, being secured thereto by means of a suitable 85 screw 16^b. The ends of the ribbon pass through an aperture 16^a in the collar 16 and through the casing of the latch bar at 38, abutting the end of the bar 29. The spindle 14 is squared as it enters the collar 90 16 so that any movement thereof will be communicated directly to the collar, whereas the spindle 15 is preferably cylindrical and adapted to move freely within the collar 16, without imparting its movement thereto. 95 These spindles meet within the collar and abut, as shown in Figs. 6 and 7. A key 39 (substantially round in cross-section) extends longitudinally through the spindle 14, terminating in a head 39^a, as shown. This 100 key is operable from the inside, its head being drawn from or inserted into a spline-way 40 in the end of the spindle 15, so that the movement of the spindle 15 may be communicated through the key 39 to the shaft 105 14 and thereby to the collar 16. A lock cylinder 41 is provided within the outer door knob 13 and by means of this lock cylinder a key 42, similar to the above referred-to key 39, is tensionally secured within the 110

spindle 15 by means of a contracting spring 42^a, as shown. The last mentioned key 42 is provided with a slot in the inner end thereof, which is adapted to receive or engage the head 39^a of the key 39.

From the foregoing it will be apparent that when a key, such as is designated by the reference character 50, is inserted into the lock cylinder 41, it will bear against the 10 end of the key 42, thus forcing it into engagement with the headed end of the key 39, which will permit the operator to then turn the outside door knob 13 and thereby control the movement of the lock and latch 15 mechanism. However, when it is desirous to lock the door from the outside, the operator will insert the key as before and by forcing the key 42 against the key 39, he will force the head 39^a from the splineway 20 40 and then upon extracting the key 50, the key 42 will be retracted in place through the instrumentalities of the spring 42^a, thus leaving the spindle 15 to rotate freely within the collar 16.

25 In order to positively lock the movement of the latch bar 26, I provide a spring pressed plunger or key 43, which passes through the casing 10 of the lock and engaged recess 44—45 in the bar 29 (Fig. 2).

30 It will now be apparent, that as the collar 16 is rotated, the ribbon 37 will force the bar 29 forward, thus releasing the grapples 32—33 from the rod 36, and simultaneously therewith the lug 17 will bear against 35 the lug 18, and will cause the movement of the latch plate 19, which being connected to the latch bar 26 by the lever 22, by the three point bearing 23—24—25, will cause the latch bar to recede from the keeper 27, thus unlatching and unlocking the door.

40 Having thus described my invention, it will be apparent to those skilled in the art to which it appertains, that many modifica-

tions may be made therein and still come within the scope of the appending claims. 45

What is claimed is:—

1. A lock comprising a latch bolt, and means for reciprocating same into and out of a keeper, a transverse rod disposed within said keeper, and means for locking said latch bolt to said rod, said last mentioned means comprising grapples pivoted to said latch bolt, a reciprocable bar mounted within said latch bolt, a link connecting said bar with one of said grapple members, the other of said grapple members slidably engaging the inclined front of said bar, and means for reciprocating said bar, within said latch bolt. 50

2. A lock comprising a latch bolt, and means for reciprocating same into and out of a keeper, a transverse rod disposed within said keeper, and means for locking said latch bolt to said rod, said means comprising a rotatable barrel with radially projecting lugs thereon, a latch plate having projections engaged by said lugs, a link pivoted to said latch at two points, a contraction spring connecting said link with the casing of said lock, said last mentioned means comprising grapples pivoted to said latch bolt, a reciprocable bar mounted within said latch bolt, a link connecting said bar with one of said grapple members, the other of said grapple members slidably engaging the inclined front of said bar, and means for reciprocating said bar within said latch bolt. 60 65

70 In testimony that I claim the foregoing as my own I have hereto affixed my signature in the presence of two subscribing witnesses. 75

MARGARET B. WILLIAMS.
